SAFETY GRILLE

Paul C. Reilly, West Berlin, N. J., and Fowler H. Cardwell, Philadelphia, Pa.

Application May 8, 1945, Serial No. 592,584

1 Claim. (Cl. 20—71)

1

This invention relates to safety grilles, and more particularly to a safety grille useful as a guard across open windows, doorways, and the like.

The primary object of our invention is to provide an improved safety grille which can be readily attached to window frames to prevent persons, and particularly children, from falling out of open windows; which will protect window panes against being broken by children at play; and which will act as a deterrent or obstacle to the entrance of sneak thieves or other unauthorized persons through an open window.

More particularly, it is an object of our invention to provide an improved safety grille or guard as aforesaid which is adjustable for accommodation to windows and doorways of various sizes and which can be installed in a facile manner even by one not especially skilled in the handling of tools.

Another object of our invention is to provide an improved safety grille which can be marketed in a knocked down condition and can be assembled readily for easy adjustment and installation.

Still another object of our invention is to provide an improved safety grille as above set forth which can be attached to window frames, doorways, or the like without requiring any permanent alteration or defacement of the window frame, door frame, or similar structure.

A further object of our invention is to provide an improved window guard which will act as a strong, rigid barrier when installed on a window frame, yet can be removed quickly and easily when the window is to be washed or when, for any other reason, its presence is not desired.

Still a further object of our invention is to provide an improved safety grille which, when installed, will permit substantially the same degree of ventilation as though it were not present.

It is also an object of our invention to provide an improved safety grille as set forth above which is exceedingly simple in construction, inexpensive in cost, and highly efficient in use.

According to one form of our invention, we provide an adjustable frame which carries a plurality of spaced rods or bars running either horizontally or vertically between the frame pieces. In a preferred construction, the frame may consist of two side or end pieces, a top piece and a bottom piece. The top and bottom pieces may be secured to one of the side pieces, while the other side piece is adjustably received on the top and bottom pieces of the frame, the last mentioned side piece thus being adjustable longitudinally

2

along the top and bottom pieces. A plurality of guard rods or bars extend in parallel relation through suitable openings in the last mentioned side piece and are preferably secured to the first mentioned side piece, whereby the movable or adjustable side piece is also slidable along the parallel rods as well as along the top and bottom frame pieces.

The assembly may be sold in knocked down condition. When the grille or guard is to be set up for use, the top and bottom frame pieces and the parallel rods or bars therebetween are first inserted into appropriate openings or slots in the stationary side piece of the frame and are secured thereto by screws or any other suitable means. The adjustable side piece of the frame is then mounted on the top and bottom frame pieces and receives the free ends of the parallel rods or bars through appropriate openings therein. The adjustable frame piece may then be slid along the top and bottom frame pieces to the desired position for accommodation of the frame to the width of a selected window or doorway after which the adjustable side piece is secured in place to each of the top and bottom frame pieces as well as to the intervening bars or rods by means of additional screws or the like. The protruding ends of the top and bottom frame pieces and of the intervening bars or rods may then be cut off, if desired, or they may be retained at full length in the event that the guard or grille is later to be used on a window or doorway of greater length or width. The frame and the rods or bars carried thereby may be made of wood, metal, plastics or any other suitable material. Mounting of the grille may be accomplished by means of suitable mounting brackets carried by the side pieces of the frame for cooperation with substantially inconspicuous mounting members carried by the framework of the window or doorway.

The novel features that we consider characteristic of our invention are set forth with particularity in the appended claims. The invention itself, however, both as to its organization and method of operation, as well as additional objects and advantages thereof, will best be understood from the following description of one embodiment thereof, when read in connection with the accompanying drawing in which

Figure 1 is a front elevation of an assembled window guard constructed in accordance with one form of our invention.

Figure 2 is an end view thereof as seen from the right of Figure 1.

Figure 3 is an enlarged, fragmentary, end view of the lower portion thereof showing one way in which the guard may be mounted in place on the window frame.

Figure 4 is a perspective view of a window with one of our improved guards mounted in place on the window frame, and

Figure 5 is an enlarged, perspective view of the mounting bracket of Figure 3.

Referring more particularly to the drawing wherein similar reference characters designate corresponding parts throughout, there is shown a grille useful as a window guard and comprising a rectangular frame having two upright end members 1 and 3, a top member 5 and a bottom member 7. The upright member 1 is provided with slots or channels 9 and 11 and a plurality of recesses or openings 13 which extend thereinto a suitable distance short of its width (for example, about two-thirds or three-fourths of its width). The top and bottom frame members 5 and 7 are received, respectively, in the slots 9 and 11 in parallel relation to each other and are secured to the frame member 1 in any suitable manner, as by screws 15. Within the openings 13 are received a plurality of parallel rods or bars 17 arranged in parallel relation with the top and bottom frame members 5 and 7 and constituting guard members. The guard members 17 may also be secured to the upright frame member 1 by screws 15 or the like. Thus, the frame parts 1, 5 and 7 and the guard members 17 constitute a rigidly coupled unit with the frame parts 5 and 7 secured to the frame part 1 in fixed relation thereto.

The upright frame part 3 constitutes the adjustable member of the frame. For this purpose, the frame part 3 is provided with slots or channels 19 and 21 which extend entirely therethrough (as best seen in Figure 4) and respectively receive the upper and lower frame parts 5 and 7. Thus, the upright frame part 3 can be slid longitudinally along the frame parts 5 and 7 for adjustment of the frame to the size required for a particular window or doorway. The frame member 3 is also provided with a plurality of openings 23 which extend entirely therethrough in alignment with the openings 13 and which receive the guard rods or bars 17. Hence, when the frame member 3 is adjusted along the frame parts 5 and 7, it is simultaneously also adjusted longitudinally along the guard members 17. The frame member 3 may be secured to the parallel frame parts 5 and 7 and the guard members 17 in any selected position of adjustment thereon by screws 25 or any other suitable means. By merely loosening the screws 25, the frame part 3 may be easily adjusted later to some other suitable position on the frame members 5 and 7 and the guard members 17, if desired.

The frame members 1 and 3 are provided with mounting brackets 27 by means of which the assembled grille or guard may be mounted on a suitable supporting structure, such as a window frame 29. To this end, the brackets 27 may be formed with inverted key hole slots 31 for cooperation in well known manner with small, inconspicuous, mounting screws 33 which are screwed into the window frame 29 or other suitable supporting structure at appropriate points thereon.

A grille or guard as above described may be sold in knocked down or disassembled condition. To set it up for use, it is merely necessary to place the frame parts 5 and 7 into their respective slots

or channels 9 and 11 and secure them to the frame part 1 by the screws 15. Similarly, the rods or bars 17 are inserted into the openings 13 and secured to the frame part 1 by like screws 15.

5 The frame part 3 is then slid onto the upper and lower frame parts 5 and 7 whereupon it will receive the guard members 17 in the openings 23 thereof, and the frame part 3 is then adjusted to the desired position on the frame parts 5 and 7 and the guard members 17 and releasably locked thereto by the screws 25. Thereafter, the screws 33 are screwed into the window frame 29 in proper locations and the grille is mounted on the screws 33, in laterally spaced relation to the window, as clearly shown in Figures 3 and 4, by means of the brackets 27 to provide a firm, rigid, sturdy window guard that will effectively protect persons from falling out of the open window, as shown in Figure 4. The guard will also serve as a deterrent to entrance through the open window of sneak thieves or other unauthorized persons. At the same time, it will be observed that our improved window guard does not appreciably reduce ventilation through the open window. Furthermore, when the window is closed while the guard is in place, the guard will protect the window panes against accidental breakage, as by children at play.

30 A window guard as described above can be assembled and installed in but a few minutes with the aid of conventional tools customarily found in the house, even by one not skilled in the handling of such tools, and it can be disassembled for storage just as easily. If desired, the ends of the frame members 5 and 7 and the guard members 17 which protrude beyond the frame member 3 (shown in dot-and-dash lines in Figure 4) may be cut off flush with the frame member 3 after the latter has been secured in adjusted position. On the other hand, these protruding ends may be left intact if the grille is also to be used at times on wider windows or doorways. Our improved grille permits of adjustment over a wide range and its utility is therefore greatly enhanced.

40 Although we have shown and described but a single embodiment of our invention, it will undoubtedly be apparent that many other forms thereof, as well as various changes in the particular embodiment described herein, are possible. We therefore desire that our invention shall not be limited except insofar as is made necessary by the prior art and by the spirit of the appended claims.

45 We claim as our invention:

A safety grille for an opening having a movable closure, said grille comprising, in combination, a single, rectangular frame structure including (1) two parallel parts, (2) a third part secured to said parallel parts and constituting one end member of said frame structure, and (3) a single fourth part constituting the opposite end member of said frame structure, a plurality of parallel guard members secured to said third frame part and extending in parallel relation to said parallel frame parts, said fourth frame part being carried solely by said two parallel frame parts and by said guard members and being adjustable on and along the full lengths of each of said two parallel frame parts and said guard members, means for securing said fourth frame part to each of said parallel frame parts and said guard members in any selected position of adjustment thereon, and mounting elements on said third and fourth frame parts for

mounting said grille on a supporting structure behind said closure in laterally spaced relation to said closure whereby said closure is free to be opened and closed while said grille remains in place on said supporting structure.
